C. B. FAIRCHILD

AUTOMOBILE HEADLIGHT

Filed April 24, 1926

FIG 2

FIG 1

INVENTOR
Charles Booth Fairchild
BY
Sennies & Sennies
ATTORNEYS

UNITED STATES PATENT OFFICE.

CHARLES BOOTH FAIRCHILD, OF CHICAGO, ILLINOIS, ASSIGNOR OF ONE-HALF TO
LOUISE A. MOORE FAIRCHILD, OF CHICAGO, ILLINOIS.

AUTOMOBILE HEADLIGHT.

Application filed April 24, 1928. Serial No. 104,344.

This invention relates to automobile headlights.

An object of the invention is to provide a headlight devoid of imparting glaring rays, and yet one which will fully light a road in an efficient manner.

Another object of the invention is to provide an automobile headlight so constructed as to utilize rays from a parabolic reflector projected to light a road without the use of lenses or shields, or other devices of such a nature commonly employed to reflect, focus and cut off the light rays not employed to light the road.

15 A further object of my invention is to provide a headlight which has the advantage of directly focusing the light rays upon the road, a headlight which is highly efficient in operation, yet of marked simplicity as a whole and in respect to each of its component parts, that its manufacture may be economically facilitated both as regards to parts and their assembly.

With these and other objects in view 25 which may be incident to my improvements, the invention consists in the parts and combinations to be hereinafter set forth and claimed.

In order to make my invention more 30 clearly understood, I have shown in the accompanying drawings means for carrying the same into practical effect, without limiting the improvements in their useful applications to the particular constructions, 35 which for the purpose of explanation, have been made the subject of illustration.

In the drawings forming a part of this specification:

Figure 1 is a side elevation of my improved automobile headlight, and

Figure 2 is a sectional view of Figure 1 taken through the center.

Referring by numerals to the drawings, 1 represents a cylindrical section having 45 formed upon one end thereof and integral therewith a conical shaped housing 2. The housing 2 is provided with a circular flange or collar 3, the object of which will herein-after appear.

50 Mounted in the cylindrical section 1 is a socket 4. The socket 4 is mounted in the section 1 with one of its ends projecting

into the housing 2, as clearly shown at 5. This socket is adapted to receive, and is provided with means to retain, in its respective ends, a lamp 6 and a contactor, not shown.

55 Mounted upon the end 5 of the socket 4 is a reflector 7. The reflector 7 is fitted tightly upon the socket 4 and is of such 60 configuration as to fit snugly back of the lamp bulb. The edge of the reflector is provided with a flange 8 which bears against and is flush with the edge of the flange 3, the purpose of which will hereinafter appear.

65 A circular diaphragm 9 having a central aperture 10 and a sleeve or collar 11 bears against the flange 8 upon the reflector 7. The sleeve 11 on the diaphragm fits snugly 70 over the flange 3 and is secured thereto by means of screws 12. Thus the reflector is supported in a rigid position by binding the rim or flange 8 between the edge of the flange 3 and the diaphragm 9. The periphery 75 of the diaphragm is provided with a threaded portion 13, the purpose of which will hereinafter appear, and the aperture 10 in the diaphragm is so located as to form between its wall and the flange 8 a shoulder 80 14.

85 Mounted upon the threaded portion 13 on the periphery of the diaphragm 9 is a housing 15. The housing 15 may be of any desirable design, however, the form shown which is substantially elliptical is preferred. The housing 15 is open at its end opposite its mounting, and threaded or otherwise secured in the open end of the housing is a 90 sleeve 16 having a flange 17 so formed as to provide an aperture 18 of the same diameter as the aperture 10.

95 The apertures 10 and 18 are in alignment, and mounted therein is a cylindrical section 19, the interior of which is enameled in a dull white, the object of which is to secure the advantages of a reflective surface to utilize the luminosity of the light source. One end of the cylindrical section 19 engages the shoulder 14 and thereby forms a neat connection with the reflector 7. The other end of the cylindrical section 19 projects through the aperture 18 and is flush with the flange 17. Bearing against the flange 17 and the

2
end of the cylindrical section 19 are felt washers 20. The washers 20 provide a seat for the glass 21 which is held in position by a sleeve or collar 22 mounted in the sleeve 16, and secured in position by screws 23 or any other desirable means.

Mounted upon the cylindrical section 1 is a sleeve or collar 24 which carries an integral shell or housing 25 abutting the shell 10 or housing 15 threaded or otherwise secured to the diaphragm 9. The shell or housing 25 is retained in position by the screws 26 which pass through the sleeve 24 and are threaded into the section 1, or other means 15 of securing the shell or housing 25 may be provided.

The cylindrical section 19 is supported in the shell or casing in alignment with the reflector; thus the lamp which is mounted 20 centrally with respect to the reflector is in alignment with the axis of the cylinder. It will thus be evident that the utilization of light rays coming from the reflector and the projection thereof in such a manner as to 25 eliminate glare is accomplished.

While I have shown and described the preferred embodiment of my invention, I wish it to be understood that I do not confine myself to the precise details of construction 30 herein set forth, by way of illustration, as it is apparent that many changes and variations may be made therein, by those skilled in the art, without departing from the spirit

of the invention, or exceeding the scope of the appended claims.

Having thus described my invention, what I claim as new and desire to secure by Letters Patent is:

1. An automobile headlight comprising a casing, a support mounted in the casing, the support having a housing integral therewith, a rim upon the housing, a parabolic reflector mounted upon the rim within the housing, a diaphragm mounted upon the rim, the diaphragm clamping the reflector to the housing, a cylindrical member mounted at one end in the diaphragm, the cylindrical member bearing against the reflector and means for supporting the other end of the cylindrical member within the casing.

2. An automobile headlight comprising a casing, a support mounted in one end of the casing, a housing integral with the support, a flanged rim upon the housing, a reflector mounted in the housing, the reflector bearing against the rim of the housing, a diaphragm mounted on the rim, the diaphragm clamping the reflector to the housing, a cylindrical member, one end of the cylindrical member mounted in the diaphragm, the cylindrical member bearing against the reflector and means within the casing for supporting the other end of the cylindrical member.

In testimony whereof I affix my signature.

CHARLES BOOTH FAIRCHILD.
